UNITED STATES PATENT OFFICE.

FRANK A. WELLS, OF FLORENCE, KANSAS.

COTTON-SEED HULLER.

SPECIFICATION forming part of Letters Patent No. 731,988, dated June 23, 1903.
Application filed October 23, 1902. Serial No. 128,455. (No model.)

To all whom it may concern:

Be it known that I, FRANK A. WELLS, a citizen of the United States, residing at Florence, in the county of Marion, State of Kansas, have 5 invented certain new and useful Improvements in Seed-Hullers, of which the following is a full, clear, and exact description.

In this class of machines when the knives of the cylinders are changed to a sharp edge 10 such change invariably throws the cylinders more or less out of balance, and in order to balance the cylinders it is necessary to remove them from the machine and suspend them upon suitable supports, so as to note the heavy 15 point in the circumference in order to correct them, and having evenly-balanced cylinders, so as to secure the most efficient work in a machine of this character. Most machines of this character are mounted upon 20 very small platforms, and as a result there is not sufficient room upon said platforms upon which to mount the cylinder outside of the machine to balance it, thus necessitating removing the cylinder to the floor, which is 25 an expensive operation and often very inconvenient.

It is the purpose of my invention to avoid the objections above noted by means which will be hereinafter described, whereby the 30 cylinder may be balanced within the machine; and with the objects stated and minor objects my invention consists of the parts and combinations of parts, as will be hereinafter more fully set out.

35 In the drawings, Figure 1 is a side elevation of the cotton-seed huller with my invention embodied. Fig. 2 is a similar view showing the cylinder in position to be balanced. Fig. 3 is an elevation of the casting forming 40 part of the machine. Fig. 4 is a top plan view of the casting shown in Fig. 3. Fig. 5 is a detail view, and Fig. 6 is a side elevation, of the clamp which fastens around the outside of the concave knives. Fig. 7 is a side elevation 45 of a clamp. Fig. 8 is a perspective view of my machine, showing the cylinder in dotted lines elevated in a position for balancing.

1 represents the frame, two opposite sides of which are provided with a circular opening 2, in which the journal of the cylinder 3 is journaled, said cylinder being provided with knives of the usual pattern—such, for

instance, as disclosed in several of my patents, most notably in Patent No. 236,470, dated January 11, 1881. The sides in which 55 the cylinder is journaled are cut away, as at 4, in order that the journal-bearings may be introduced into the circular opening 2.

5 is a casting substantially L-shaped, having legs 6 7, the leg 7 being beveled on one 60 side to correspond with the cut-away portion in the sides of the casings, while the lower end of said leg is concave, as at 8, in the same arc as opening 2, thus completing the outline of the circular opening in which the journal is 65 secured, said concave portion 8 bearing down upon the journal and preventing its vertical displacement. The leg 6 of the casting 5 is provided with a flange 9, which is adapted to be secured by bolts 10 to the side of the casing 1, as shown in several of the figures in the drawings. It will be noticed that the upper edge of the casting 5 is straight throughout its length and that said casting is of such length that it extends from one edge of the 70 journal in the opening 2. 11 is a casting having a depending flange 12, by means of which said casting is secured to the upper edge of the casting 5. Said casting 11 is adapted to 75 be fastened to the apron usually employed in machines of this character, said aprons forming the top of the hulling-machine.

When it is desired to change the knives or sharpen them, it is always necessary to balance the cylinder in order that the machine may do perfect work, and, as stated, it has heretofore been a very expensive as well as inconvenient and laborious job to balance these cylinders. In the present machine 90 when it is desired to balance the cylinder it is only necessary to remove the casting 11 from the casting 5, remove the casting 5 from the sides of the machine, elevate the cylinder, so that its journals are above the plane of the 95 top of the machine, and then replace the castings 5 in their proper position in the sides of the casing, the top of said casting providing a perfect straight edge from end to end to a point beyond the center of the working position of the cylinder, whereby the cylinder may be lowered upon said straight edge of the casting 5 and balanced in that position within the outlines of the machine, thus ob-

viating the necessity of entirely removing the cylinder to some distant point to secure a proper support. The journals of the cylinder rest directly upon the top of the straight edge of the casting 5 in the position immediately over that which they occupy in their working position. As soon as the cylinder is properly balanced it is again elevated by suitable hoisting mechanism, castings removed, 10 and the cylinder then lowered until the journals are within the openings 2, the castings again replaced and secured by means of the bolts 10 to side of the machine, and the casting 11 secured to the straight edge of the casting 5 by means of the bolts 12, and finally the press secured in its position.

Thus it will be seen that while my invention is very simple at the same time it is a very effective one and obviates needless transporting of parts and the expense incident thereto.

In Fig. 7 I have illustrated a form of clamp adapted to fasten around the outside of the concave knives. This clamp is constructed in two sections 13 14, the clamp 15 having 25 one of its faces in an arc whereby the passage of a bolt 16 through the center of said clamp guides the clamps 13 and 14 in a circle.

After the huller has been run some length of time the knives naturally become dull, and 30 therefore have to be turned to a sharp edge. Invariably when the knives are changed the cylinder is thrown out of balance, and in order to rebalance the machine the center bolt 8^a is removed from the cylinder and the screw-eye 8^b secured in its place, said screw-eye being provided with a chain 8^c, attached to a suitable hoisting mechanism. When the caps or plates 5 are removed and laid aside, the cylinder is then hoisted by means of a chain 35 8^c out of its bearing—say a foot above the frame—the plates 5 are then replaced in their proper position and suitably secured in the sides of the machine, the tops of the castings 5 providing straight edges on each side of the 40 machine upon which the cylinder is lowered 45

and supported, the cylinder being free to be manipulated upon said straight edge, so as to secure a proper balance, the balance being attained by means of suitable balancing-weights in the interior of the cylinder, said 50 balancing-weights being common and in practice, and therefore not claimed or shown in this application. During the balancing of the cylinder the eyebolt 8^b is detached therefrom, so as to leave the cylinder free to revolve. After 55 the cylinder has been properly balanced the eyebolt 8^b is again attached to the cylinder in order that the cylinder may be elevated by means of the chain 8^c and suitable hoisting mechanism, so that the plates 5 may again be 60 removed to permit lowering of the cylinder into its proper bearings in the machine, and as soon as it is in this position the plates 5 are again replaced and suitably secured as described and the eyebolt 8^b and the chain 65 removed.

Having thus described my invention, the following is what I claim as new therein:

1. In a machine of the character described, having cut-away portions in two of its sides, 70 in which the cylinder is journaled, a removable L-shaped casting having an upper straight edge and adapted to fit within said cut-away portion.

2. In a machine of the character described, 75 the combination of a casing, two sides of which are cut away to form journal-bearings, for the cylinder, of an L-shaped casting constructed to be detachably secured in said cut-away portions, and having a straight upper 80 edge extending beyond the center of the journal-bearing so as to form a bearing upon which the cylinder may be balanced within the lines of the machine.

The foregoing specification signed this 24th 85 day of September, 1902.

FRANK A. WELLS.
